UNITED STATES PATENT OFFICE

105,578

DESIGN FOR A COMBINATION BACK SPLASH PANEL, WARMING CLOSET, AND SUPPORTS FOR SAME

Rives Fleming, Richmond, Va.

Application June 10, 1937, Serial No. 69,779

Term of patent 14 years

To all whom it may concern:

Be it known that I, Rives Fleming, a citizen of the United States, residing at Richmond, in the county of Henrico and State of Virginia, have invented a new, original, and ornamental Design for a Combination Back Splash Panel, Warming Closet, and Supports for Same, of which the following is a specification, reference being had to the accompanying drawing, forming part thereof.

The figure is a perspective view of a combination back splash panel, warming closet and supports for same, showing my new design.

I claim:

The ornamental design for a combination back splash panel, warming closet, and supports for same as shown.

RIVES FLEMING.
